TEMPERATURE CONTROLLING MEANS FOR
RAILWAY CARS

Joseph F. Frese, Baltimore, Md., assignor to Monitor Controller Company, Baltimore, Md., a corporation of Maryland

Application April 6, 1936, Serial No. 73,024

4 Claims. (Cl. 236—1)

This invention relates to electrically operated means for maintaining the air in railway passenger cars at a desired temperature either in warm or cold weather while the car is in service, and for maintaining a suitable temperature in the car while the car may be out of service in cold weather. In carrying out the invention, I provide an air cooling system for use in warm weather comprising a compressor for compressing refrigerating fluid, a condenser and a refrigerating coil, a motor for operating the compressor, one or more motors for circulating cooling fluid around the condenser and one or more fan motors for circulating the air in the car past the refrigerating coil to cool the air and thermally controlled means for starting the compressor motor and the condenser motors when the temperature in the car is above a desired normal and for stopping these motors when the temperature falls to said desired normal. Such cars are provided with steam pipes through which steam is carried from the locomotive to suitable radiators in the car, to heat the car in cold or chilly weather, and I provide thermally controlled electro-magnetic means for automatically opening a valve in the heating system when the temperature of the air in the car falls below the aforesaid desired normal temperature and for closing the valve when the temperature is about normal. Thus, in changeable weather, while the car is in service, the heat controlling means may operate to raise the temperature of the air in the car to a desired normal at one time and the cooling system may operate to lower the temperature of the air in the car at another time on the same day or on different days. I provide interlocking connections whereby by the heating and cooling system cannot operate simultaneously and also means whereby, when the car is uncoupled from a train and placed in storage, the cooling system cannot operate, but the heat controlling means may operate providing the steam pipe is connected to a suitable steam generator.

In the accompanying drawing which illustrates the system diagrammatically, *a* indicates a compressor for compressing the refrigerating fluid, *a'* indicates a condensing coil and *a²* indicates a refrigerating coil, these coils being in series in a circulating pipe system *a³* connected to the compressor. A high pressure valve *a⁴* at the high pressure side of the compressor opens and relieves the pressure if it becomes abnormally high. An electric motor *b* is provided for operating the compressor; one or more motors *c* are provided for circulating cooling fluid around the condenser, and one or more fan motors *d* are provided for circulating the air in the car past the refrigerating coil, to cool the air. The train-pipe of the air brake system is indicated at *e* and a pipe forming a part of the heating system is shown at *f*.

and one or more fan motors *g* are provided for circulating the air of the car over the heat radiating surfaces. The supply wires leading from a current source such as a battery or generator on the car are indicated at *L* and *L'*.

To provide for keeping the temperature within the car at a suitable degree above the freezing temperature while the car may be stored or out of use in the winter time, the steam pipe *f* may be connected to a suitable stationary heating plant and the temperature will then be regulated automatically by electromagnetic valve actuating means controlled by a thermostat. As shown, a valve *1* is arranged in the steam pipe *f* and this valve is movable to the closed position by an electromagnet *2* and to the open position by an electromagnet *3*. The armatures of the electromagnets are connected to a valve lever *4* and this lever has at its free end a contact piece *5* which electrically connects stationary contacts *6* and *7* when the valve is in closed position, and which electrically connects stationary contacts *8* and *9* when the valve is in the open position. Contact *6* is connected by conductor *10* to the coil of magnet *3* and thence to supply wire *L* by conductor *11*, and contact *8* is connected to coil of magnet *2* and thence to supply wire *L* by conductor *12*. Contact *7* is connected by conductor *13* to stationary contact *14* of relay *h* and contact *9* is connected by conductor *15* to relay contact *16*. The relay *h* has a contact arm *17* which normally engages contact *16* and which is movable into engagement with contact *14* when the magnet *18* of the relay is energized. The relay also has a contact arm *19* which is movable with the arm *17* but which performs no function when the car is in storage and disconnected from the locomotive. The circuit for the magnet of relay *h* extends from supply wire *L* through conductor *20* to the magnet coil and thence by conductor *21* to the supply wire *L'*. Included in the part *20* of this circuit is a manually operable switch *22* and a thermostat switch *23*.

When the car is in storage in cold weather, steam will be admitted to the pipe *f* of the heating system of the car from a stationary heating plant. To keep the air in the car above the freezing temperature, the manually operable switch *22* will be closed to make up the circuit to the coil of relay *h* through the thermostat switch *23* which closes at a predetermined low temperature and opens at a predetermined high temperature in the car. When the thermostat switch closes, the relay magnet is energized and the contact arm *17* is moved out of engagement with the contact *16* and into engagement with the contact *14*. This completes a circuit to the coil of the valve operating magnet *3* from supply wire *L* through the magnet coil and by conductor *10* through contacts *5*, *6* and *7*, conductor *13*, con-

tact 14, switch arm 17 and conductor 21 to supply wire L'. Magnet 3 immediately moves the valve to open position to admit steam to the heating system of the car. In moving to open position, 5 the contact member 5 on the valve lever opens the circuit to magnet 3 and makes up a circuit to magnet 2 at the contacts 8 and 9, but this latter circuit is open at the relay contact 16 and remains open as long as the thermostat is closed 10 and the relay magnet is energized. When the temperature in the car rises sufficiently to cause the thermostat switch to open the circuit of the relay magnet, the relay arm 17 moves into engagement with contact 16, thus completing the 15 circuit to the valve operating magnet 2 through the contact 5 on the valve lever and the contacts 8 and 9. Magnet 2 then moves the lever to close the valve, at the same time opening the circuit through its coil and making up a circuit to the 20 coil of magnet 3 at the contacts 6 and 7, but this latter circuit is then open at the relay contact 14 and remains open until the thermostat switch again closes the circuit of the relay magnet. Thus, each valve operating magnet, after moving 25 the valve, opens its own circuit and makes up a circuit for the opposing magnet, and current is on the magnets only momentarily, in the normal working of the apparatus.

When the car is out of service in cold weather 30 and heat is supplied from an external source, as there are no passengers in the car, it is unnecessary to operate the fan motors *g* to circulate the air in the car and therefore the connections are such that these motors can be operated only when 35 the car is coupled in a train. In warm summer weather, the heating system will not be required, whether the car is idle or in service, and therefore the switch 22 will be left open so that the relay *h* which controls the steam valve and also 40 forms a part of the controlling means for the motors *g* will be inoperative.

When the car is in service, the pipe *f* will receive steam from the locomotive and the train pipe *e* of the air brake system will contain air 45 under pressure. A switch 24 which is always open when the car is disconnected from the locomotive, is always closed by the air pressure in the train pipe when the car is coupled to a locomotive. Through this switch and interlocking connections, 50 circuits are made up for operating the heated air fan motors *g* when the car requires heating and the steam valve is open, or for operating the fan motors *d* when the heat is not required and the steam valve is closed. In order to cause operation 55 of any of the fan motors, *g* or *d*, a push button switch marked "Fan" must first be closed in order to close a relay *i*.

As shown, a circuit extends from supply wire L through conductor 25 and a normally closed 60 switch marked "Stop" and through conductor 26, switch 24 and conductor 27 to coil of magnet 29 of a relay *j*, thence by conductor 30 to stationary contact 31 of relay *h*. A conductor 33 extends from conductor 27 to coil of magnet 28 of a relay 65 *k* and thence to stationary contact 32 of relay *h*. The contact arm 19 of relay *h* rests against contact 31 when the steam valve is closed and is movable into engagement with contact 32 when the steam valve is opened. A conductor 34 connects 70 said contact arm to the contact arm 35 of the normally open relay *i*. When relay *i* is closed, conductor 34 is connected through conductors 36 and 37 to supply wire L'. Hence, if contact arm 19 of relay *h* is in engagement with contact 31 75 and relay *i* is closed, current will flow through

the coil of magnet 29 of relay *j*, and if contact arm 19 of relay *h* is in engagement with contact 32, current will not flow through the magnet coil of relay *j* but will flow through the magnet coil of relay *k*. Relay *j* has a contact arm 38, normally 5 in open position, adapted to engage contact 39 when the relay is closed. Contact 39 is connected by conductor 40 to the fan motors *d* which are connected to supply wire L and contact arm 38 is connected by conductor 41 to supply wire L', 10 so that when said relay closes, these motors will operate. Contact arm 42 of relay *k* is connected by conductor 43 to the heated air fan motors *g* which are connected to supply wire L, and when the relay closes, it will connect the motors *g* through conductors 44 and 21 to supply wire L' and these motors will operate to circulate the 15 air of the car past the heating surfaces.

As before stated, the "Fan" push button must be depressed to energize the magnet of relay *i* 20 and cause this relay to close in order that either of the relays *j* or *k* can be closed to operate the motors *d* or *g*. The normally open "Fan" push button switch is arranged in a conductor 37^a which extends from conductor 26 to a resistance 25 45 and coil 46 of a low voltage relay *m*, which resistance and coil are connected by conductor 37 to supply wire L'. Normally, depression of the "Fan" button causes the relay magnet to be energized and its arm 47, which is connected by conductor 48 to conductor 26, closes a holding circuit 49 for the magnet coil 46 and also connects conductor 48 to conductor 50 which leads to the coil of magnet 51 of relay *i* and thence by conductor 37 to supply wire L'. Depression of the 35 "Fan" push button switch therefore causes relay *i* to close and complete the circuit from contact arm 19 of relay *h* through conductor 34, contact member 35, contact 36 and conductor 37 to supply wire L'. While this condition exists, as 40 long as contact arm 19 is in normal position against contact 31, the relay *j* will be energized and the fan motors *d* will operate; but if low temperature causes thermostat 23 to close and relay *h* to shift the arm 19 to contact 32, fan motors *d* 45 will stop and motors *g* will operate. Depression of the "Stop" push button will open the circuit to the low voltage relay coil and the relay will open the circuit to the magnet coil of relay *i*, which relay will open the circuit to arm 19 of relay *h* and hence no current can flow to the magnets of relays *j* or *k* and the fan motors in operation at the time the "Stop" switch is depressed 50 will be stopped.

In warm weather the thermostat switch 23 of 55 the heat controlling means will remain open and the relay *h* will not operate, hence contact arm 19 will remain in engagement with contact 31 and the air circulating fan motors *d* will operate after depression of the "Fan" push button. 60 These fan motors may be operated to circulate air in the car without operating the refrigerating apparatus, but the interlocking connections are such that they must be in operation before the compressor motor and condenser motors can 65 be operated. This is to avoid the possibility of operating the compressor without having the fans in operation to circulate the air over the refrigerating coils.

After the circulating fan motors *d* have been 70 started by depression of the "Fan" push button switch, another push button switch 52, marked "Comp.", must be depressed to condition the circuits for operating the compressor motor *b* and the condenser motors *c*. When the mo- 75

tors *d* are in operation, relay *i* is closed and the contact arm 38 of relay *j* is also in closed position and another arm 53 of the latter relay is in engagement with a contact 54 which is connected to conductor 34. Arm 53 is connected by conductor 55 to contact arm 56 of a relay *n* which is adapted to engage contact 57 when the relay is closed. This relay has an arm 58 adapted to engage a contact 59, and arm 58 is connected by conductor 63 to conductor 26 which is connected to supply wire L through the "Stop" switch. The push button switch 52 is adapted to complete a circuit from the supply wire L and conductor 26 through the push button switch 51 and conductor 61 to the coil of magnet 62, thence through conductors 60 and 34 to contact arm 35 of relay *i* and conductors 36 and 37 to the supply wire L'. When this circuit is completed by the momentary depression of the push button switch 52, contact arm 58 will close a holding circuit for the coil of magnet 62 through conductor 63 in shunt to the switch 52, and arm 56 will engage contact 57 and connect a conductor 64 to the side L' of the supply circuit through conductor 55, arm 53 and contact 54 of relay *j*, conductor 54^a, arm 35 of relay *i* and conductors 36 and 37.

Conductor 64, connected as described, to the supply wire L', when the relays controlling fan motors *d* are closed, extends to the coil of magnet 65 of a relay *o*, thence through a thermostat switch 66 and a manually controlled switch 67 to conductors 26 and 25 and thence through the "Stop" switch to the side L of the supply circuit. Thus, after the closure of the "Fan" push button switch and the compressor push button switch in succession, the magnet 65 of relay *o* will be energized, providing the thermostat switch 66 and the manually controlled switch 67 are closed. The relay *o*, which constitutes a starter for the condenser motors *c* and controls the operation of a starter *S* for the compressor motor, has a contact arm 68, normally in open position and adapted to engage a contact 69 in closed position. When the relay magnet is energized, a circuit is completed to the condenser motors *c* from supply wire L' through conductor 70 to contact 69, thence through arm 68 and conductor 71 to the motors *c* which are connected to the supply wire L, as shown. These motors will then operate. The relay also has an arm 72 adapted to engage a contact 73 which is connected to the conductor 64 and when this relay closes, the arm 72 connects the conductor 64 to a conductor 14 which leads to the contact member 75 of a retarded relay *t*. The starter *S* has contactors *s*, *s'* and *s''* for closing the armature circuit of the compressor motor and for cutting the starting resistance out of said circuit. The contactor arm 76 of contactor *s*² has an insulated contact 77 which normally rests against a stationary contact 78 connected to conductor 74 and a stationary contact 79. In its normal position, the arm of contactor *s*² completes a circuit to the coil of magnet 80 of contactor *s* from conductor 74 to contacts 77, 78, and 79 to conductor 81, thence to coil of magnet 80, thence by conductor 82 to conductor 83 and through a high pressure cut-out switch 84 and conductor 83^a to conductor 64 and thence through thermostat switch 66 and manually controlled switch 67 and through conductor 25 and the "Stop" switch to supply wire L. Hence when the relay magnet 65 is energized and the contact arm 72 of relay *o* is moved into engagement with contact 73, the

magnet 80 of contactor *s* will be energized and the contact arm 85 will be moved to closed position and will close the circuits of the compressor motor *b*.

The armature circuit of the compressor motor extends from supply wire L' through conductors 86 and 87 to contact 88 and contactor arm 85 to conductor 89 through resistances 90 and 91 to the armature 92 and thence to supply wire L. The shunt field circuit extends from the contactor arm through conductor 93 to the shunt field winding 94 and thence to the supply wire L. When the contactor *s* closes, the compressor motor starts and insulated contact 95 on the arm engages contacts 96 and 97 and connects conductor 74 to a conductor 98 which leads to the coil 99 of the retarded relay *t* and thence to conductor 83, through switch 84 to conductor 64, thence through thermostat switch 66, manually operable switch 67 and the "stop" switch to supply wire L. The retarded relay will move its contact member upward gradually, said member first engaging a stationary contact 100 and then engaging a stationary contact 101. When it engages contact 100, a circuit is completed from conductor 74 through contacts 75 and 100 to conductor 102 which leads through coil of magnet 103 of relay *s'* and thence through conductors 82 and 83, switch 84 and conductors 83^a, 64, and 25 to the supply wire L. Contactor arm 104 will close and connect conductor 86 to armature circuit 89, cutting out resistance 90. Next, contact member 75 will engage contact 101 and connect conductor 74 to conductor 105 which leads through coil of magnet 106 of contactor *s*² to conductor 82 and thence through conductors 83, 83^a, and 64 to the supply wire L. Contactor arm 76 will close and connect conductor 86 to the armature circuit 89, cutting out resistance section 91. In closing, a contact 107 on the contactor arm will establish a holding circuit for the coil of magnet 106 from conductor 74 through resistance 108, and contact 77 will break the connection between conductors 74 and 81, thereby de-energizing the magnet of contactor *s* and permitting its contactor arm 85 to move to normal position, opening the circuit to coil 99 of the retarded relay *t*. The contact member 75 of the relay *t* will drop downward, breaking the connections between conductor 74 and the magnet coils of relays *s'* and *s*². The contactor arm or relay *s'* will return to normal position but the magnet coil of contactor *s*² will remain energized through its holding circuit and the compressor motor will continue to run until the circuit through the coil of magnet 106 is interrupted at some point in the system. If the thermostat switch 66 opens, due to lowering temperature in the car, the relay or contactor *o* will open, stopping the motors *c* and the contactor *s*² will open, stopping the compressor motor, and its armature 76 will return to normal position, connecting the conductors 74 and 81, thus conditioning the circuits of the starter *S* for restarting when the circuit through conductor 64 is re-established by the thermostat switch when the temperature rises to a predetermined degree. If the high pressure cut-out switch opens, due to excessive pressure at the compression side of the compressor, the magnet 106, which receives current through the high pressure switch, will be de-energized and the compressor motor will stop, while the condenser motors will continue in operation, and when the

pressure goes down and said switch closes, the compressor motor will start.

When it is desired to stop the working of the refrigerating mechanism, the "Stop" push button 5 is depressed. This causes the low voltage relay *m* to open the circuit of the magnet of relay *i* and this relay opens the circuit to the magnet of relay *n* which opens the control circuit 64 for the compressor and condenser motors so that 10 these cannot operate. The opening of relay *i* also opens the circuit through conductor 34 to the magnet of relay *j*, causing the stoppage of the cooling fan motors *d*. To place the system in condition for operation again, it is first necessary to depress the "Fan" button, to cause closure of the relays *m*, *i* and *j*, which starts the 15 fan motors *d*. These fan motors may be operated as long as desired independently of the compressor and condenser motors. The relays *i* and *j*, when closed, make up a circuit through conductors 31, 36, 54^a, and 55 to the arm 56 of relay *n*. After the fan motors *d* have been started, depression of the push button switch 52 causes relay *n* to connect conductor 55 with conductor 64, thus 20 completing the control circuit for the compressor and condenser motors so that they may operate when the thermostat switch 66 is closed.

When the car is coupled in a train, the air pressure switch 24 is closed. If the "Fan" push 30 button is depressed and the temperature in the car is at or above a desired normal, the heat controlling device will not work because the thermostat switch 23 will be open and relay *h* will be inoperative; but the circuit to the magnet 29 of relay *j* will be complete through arm 19 of relay *h* and the fans *d* will operate when said relay closes, and upon depression of the push button switch 52, the refrigerating apparatus will operate automatically to reduce the temperature in 35 the car to the desired normal. In cold weather, however, where the temperature in the car is low enough to cause thermostat 23 to close, the relay *h* will operate to open the steam valve and also interrupt the circuit to the magnet of relay *j*, so that the cooling fan motors *d* cannot operate, and at the same time the relay *h* will close the 40 circuit to the magnet of relay *k* and the latter relay will connect the motors *g* to the supply circuit, and these motors will circulate the heated air. Since the relay *j* cannot operate while the 45 heat controlling relay is closed and the steam valve open, the circuit through contact member 53 of relay *j* to conductors 55 and 64 will remain open at relay *j*, and the compressor and condenser 50 motors cannot operate, even though the push button switch 52 be depressed after the "Fan" push button switch has been depressed. Thus, there can be no interference between the heat controlling mechanism and the air cooling system. 55 As before described, when the car is out of service, the pressure controlled switch 24 is open and neither the cooling fan motors nor the motors connected with the heat controlling means can be operated; but the heat controlling valve can 60 operate independently of the rest of the mechanism if the steam pipe *f* be connected to a stationary steam heating plant.

What I claim is:

1. In temperature regulating means for railway cars having steam heating means and an electrical supply circuit, an air cooling system comprising a fan motor for circulating cooled air in the car and a relay for connecting said motor

to the supply circuit, heat regulating means including a valve for turning on and off the steam, electro-magnetic means for operating the valve, a thermally controlled relay for controlling said latter means and a fan motor for circulating the heated air, a relay for connecting the latter motor to this supply circuit, and a circuit for the magnets of the fan motor relays, said thermally controlled relay adapted to connect the magnet of the relay associated with the first-mentioned 10 fan motor in the latter circuit when the steam valve is closed and to disconnect said last mentioned magnet and connect the magnet of the relay associated with the second fan motor in said latter circuit when the steam valve is opened. 15

2. In temperature regulating means for railway cars having steam heating means, air brakes and an electrical supply circuit, an air cooling system comprising a fan motor for circulating cooled air in the car and a relay for connecting said motor to the supply circuit, heat regulating means including a valve for turning on and off the steam, electro-magnetic means for operating the valve, a thermally controlled relay for controlling said latter means, a fan motor for circulating the heated air, a relay for connecting the latter motor to the supply circuit, a circuit for the magnets of the fan motor relays including a switch normally closed by the pressure in the air brake system while the car is coupled in a train 30 and which is normally open when the car is uncoupled, manually controlled means for closing said circuit for the relay magnets when said switch is closed, and means controlled by said thermally controlled relay adapted to connect the 35 magnet of the relay associated with the first-mentioned fan motor in the latter circuit when the steam valve is closed and to disconnect said last-mentioned magnet and connect the magnet of the relay associated with the second-mentioned fan motor in said latter circuit when the steam valve is opened.

3. In temperature regulating means for railway cars having air brakes and an electrical supply circuit, an air cooling system comprising a fan 45 motor for circulating cooled air in the car and a relay for connecting said motor to the supply circuit, a circuit for the magnet of said relay including a switch normally closed by the pressure in the air brake system while the car is coupled in a train and which is normally open when the car is uncoupled and out of service, and manually controlled means for closing said relay magnet circuit when said switch is closed.

4. In temperature controlling means for railway cars having steam heating means, air brakes and an electrical supply circuit, a valve for turning on and off the steam, electro-magnetic means for opening and closing said valve, a thermally controlled relay controlling said latter means to open the valve at a predetermined low temperature and to close the valve at a predetermined higher temperature, an electric motor for circulating the heated air, a normally open relay for closing the circuit of said motor and a circuit for 65 the magnet of the latter relay adapted to be closed by said first-mentioned relay when the steam valve is opened and the car is in service, said last-mentioned circuit including a switch which is normally closed by air pressure in the 70 brake system when the car is in service, and which is normally open for lack of air pressure when the car is out of service.

JOSEPH F. FRESE.
